US00D587358S

(12) **United States Design Patent**
Stephan et al.

(10) **Patent No.:** **US D587,358 S**
(45) **Date of Patent:** **** Feb. 24, 2009**

(54) **RADIANT FLOOR PANEL**

(75) Inventors: **John L. Stephan**, Noblesville, IN (US);
Cameron W. Cobb, Carmel, IN (US);
Barry Fawcett, Findlay, OH (US)

(73) Assignee: **Createc Corporation**, Indianapolis, IN (US)

(**) Term: **14 Years**

(21) Appl. No.: **29/284,425**

(22) Filed: **Sep. 7, 2007**

(51) **LOC (9) Cl.** **23-03**

(52) **U.S. Cl.** **D23/314**
